UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

STRIKING CASTING

Application filed November 14, 1925. Serial No. 69,092.

This invention relates to draft members and more particularly to castings adapted for attachment at the ends of center sills for the purpose of receiving draft and buffing forces.

The principal object of my invention, generally considered, is the provision of a striking casting, coupler carrier iron and cheek plates so constructed and arranged that they may be interlockingly connected together and function substantially as a single combined casting, although being separately formed.

An object of my invention is the provision of slotted cheek plates adapted for connection with the center sills of a car so that the outer ends thereof extend beyond said center sills and are formed for the reception of a top member which connects the outer ends and functions as a striking casting.

Another object of my invention is the provision of double slotted cheek plates adapted for connection with the center sills of a car at the ends thereof, each of said center sills being preferably provided with a slot registering with the slots in the cheek plates and extending to the ends of the sills, said cheek plates being formed with extensions beyond the ends of the cooperating center sills and a striking casting connecting said extensions and provided with a web or shelf extending between the center sills and adapted for connection with the center sill cover plate and end sill of the car.

A further object of my invention is the provision of slotted cheek plates connected to car center sills adjacent the ends thereof and provided with portions extending outwardly beyond said ends and formed with inwardly extending flanges, said flanges serving for the support of a coupler carrier iron between said cheek plates which carrier iron is also adapted for being held in position by a bolt extending through the same and the adjacent portions of the cheek plates.

Other objects and advantages of the invention relating to the particular arrangement and combination of the various parts

will become apparent as the description proceeds.

Referring to the drawings illustrating my invention, the scope whereof is defined by the appended claims:

Figure 1 is a plan view, partly in section, illustrating draft members constructed in accordance with my invention and connected with associated center sills.

Figure 2 is a vertical longitudinal sectional view on the line 2—2 of Figure 1.

Figure 3 is an end view.

Figure 4 is a partial side elevation showing the construction at the extreme ends of the center sills.

Referring to the drawings in detail, like parts being designated by like reference characters, the usual car center sills 1 are illustrated fragmentarily, said sills in the embodiment shown being of channel formation with upright web portions 2 and upper and lower outwardly extending flange portions 3. Said sills of the embodiment illustrated are shown each provided with a slot 4 extending to the ends thereof and of a length sufficient to provide for the reception of draft keys 5 and 6, for supporting draft gear and cushioning mechanism diagrammatically indicated, in accordance with the present embodiment, although it is obvious that I do not wish to be restricted to the use of two draft keys as one or more than two may be employed, if desired.

Cheek plates 7 are provided preferably connected to the outer sides of the webs 2 of the center sills 1 by a plurality of rivets 8. Said cheek plates are shown each provided with two slots 9 and 10 in the present embodiment, although my invention is not restricted to such a showing, it being obvious that features of the same may be embodied in cheek plates having one or more than two slots. The slots 9 are bordered or framed by flanges 11 extending therearound, said flanges serving for reinforcing the slotted portions of the cheek plates and sills and provided with inwardly extending portions snugly fitting within the slots 4 in the center sills. In the same way, slots 10 are provided with flanges 12 therearound, said

100

flanges being formed similarly to the flanges 11 around the slots 9. The flanges 11 and 12 are preferably joined by connecting flanges or webs 13 for increasing the abutment strength of the corresponding ends of the slots and rigidifying the cheek plates at these points. The rear ends of the flanges 12 around the second or inner slots 10 are preferably reinforced by tapering flange portions 14 extending diagonally upward and downward from the ends of the flanges 12, with the extreme inner rear portions thereof on the inner sides of the cheek plates curved around and filling the extreme inner ends of the slots 4 in the center sills, thereby increasing the strength of connection between said cheek plates and sills.

The forward ends of the cheek plates 7 are extended beyond the ends of the center 20 sills, as indicated at 15, said extensions being formed at their upper ends with substantially horizontal flange or web portions 16 and substantially vertical or upright flange or web portions 17, forming a seat or abutment for a top member 18, serving for connecting the upper outer ends of said cheek plates and adapted to function as a striking casting. In the present embodiment, the striking casting 18 is provided with a 30 striking web or face 19 which is increased in thickness slightly toward the central or intermediate portion thereof and a rearwardly extending shelf or web portion 20 which is preferably horizontal and the upper surface of which, when assembled, is preferably flush with the upper surfaces of the upper flanges 3 of the center sills and is adapted for extending beneath the center sill cover plate 21 and end sill 22 for suitable 40 connection therewith. Extending rearwardly from the lower edge of the striking portion 19 is a web portion 23 defining the upper edge of the opening 24 for the reception of the stem of the coupler 25. For 50 bracing the webs 19, 20 and 23, a plurality of webs 26 are preferably provided therebetween said webs 26 preferably extending longitudinally and tapering from the inner edge of the web 23 to finally merge with the shelf portion 20 adjacent the inner edge 55 thereof. At its outer ends, the striking casting 18 is preferably provided with a vertical flange or web portion 27 registering with and adapted for connection with the flange portions 17 of the cheek plates by rivets 28 and with substantially horizontal flange or web portions 29 overlying and adapted for connection with the flange portions 16 of the cheek plates by rivets 30.

60 The cheek plates 7 are preferably formed at their extreme outer ends with flanges or webs 31 flush with the adjacent portions of the striking web 19 of the striking casting 18 and serving as continuations thereof, the inwardly extending sections 32 of which

serve to define the side edges of the opening 24 beneath said striking casting.

Positioned between the extreme outer portions of the cheek plates 7 and supported on inwardly extending flanges 33 provided on 70 said cheek plates, is a coupler carrier iron 34 preferably channel shape in cross section with an upper web portion 35 and depending flange portions 36, said flange portions 36 being preferably increased in depth toward 75 the center of said member for increasing the strength thereof. The web portion 35 is likewise increased in width adjacent its intermediate portion, as illustrated in Figure 1 particularly, for increasing the bearing 80 surface provided for the coupler stem. At the ends of said member, depending web portions 37 are preferably provided and are adapted to rest on the inwardly extending flanges 33 of the cheek plates for supporting 85 the carrier iron 34. For preventing displacement of the carrier iron 34 from the flanges 33, a bolt or other connecting means 38 is preferably provided extending through corresponding apertures in the carrier iron 90 34 and cheek plates 7 and prevented from undesired removal by a nut 39.

The extreme outer ends of the cheek plate slot flange portions 11 may, if desired, be reinforced by tapering webs 40 extending between the same and the outwardly extending portions of the flanges 31. The flanges or webs 16 and 17 on said cheek plates and particularly the junction between said flanges or webs may be reinforced with 95 respect to the main web of each cheek plate by depending web or gusset portions 41. The upper portions of the webs or flanges 17 may likewise be reinforced by web or gusset portions 42 extending along the upper edges 100 of the cheek plates rearwardly of said flange portions 17.

In accordance with the foregoing disclosure, it will be apparent that I have devised draft members adapted for association with the center sills of a car and for association with each other so that, when connected together in assembled relation, they are adapted to function substantially as if they were a combined casting, provided with 110 cheek plates, striking and carrier iron portions. An advantage of not making the aforescribed portions integral but rather as four pieces, that is, two cheek plates, one striking casting and one carrier iron, resides 115 in the fact that said members may be much more readily cast individually than a combined member embodying the same.

Having now described my invention, what I claim is:

1. In combination with the center sills of a car, slotted cheek plates connected to said center sills and provided with portions extending beyond the ends of said sills and a separate striking casting connected to said 120

extensions and with a forward face forming a continuation of the front faces of the cheek plates.

2. In combination with the center sills and associated cover plate of a car, slotted cheek plates connected to the outer surfaces of said center sills and provided with portions extending beyond the ends of said sills, a separate striking casting connected to said extensions and formed with a shelf extending rearwardly between said sills for connection with said cover plate, and a carrier iron supported between said extensions.

3. In combination with the center sills of a car, slotted cheek plates connected to said sills and provided with portions extending beyond the sill ends, a separately formed striking casting connected to said extensions and formed with an upright striking face, said extensions on the cheek plates being provided with front flanges forming continuations of the striking face of the striking casting.

4. In combination with the center sills of a car, slotted cheek plates connected to said sills and provided with portions extending beyond the sill ends, said portions being formed with outwardly extending substantially horizontal flanges and outwardly extending substantially vertical flanges and a striking casting formed with corresponding flange portions at the ends thereof riveted to said horizontal and vertical flanges.

5. In combination with the center sills of a car, said center sills being formed with slots extending to the ends thereof, cheek plates connected on the outside thereof and provided with slots registering with the center sill slots and flanges bordering said slots and engaging the center sill slots, portions of said cheek plates extending beyond the ends of the sills and a striking casting connected to said extensions.

6. In combination with the center sills of a car, double slotted cheek plates connected to said center sills and provided with portions extending beyond the ends of said sills, a separate striking casting riveted to said extensions and formed with an upright striking face, said extensions on the cheek plates being provided with front surfaces forming continuations of the striking face of the striking casting.

7. A combined cheek plate and coupler carrier support slotted for receiving a draft key, adapted for connection to an associated center sill and provided with a portion adapted to extend beyond the adjacent end of said sill, and formed with means for supporting a coupler carrier, said extension being notched for the reception and support of an associated striking casting and formed with a front flange acting as a continuation of the striking face of said casting.

8. A combined cheek plate and coupler

carrier support slotted for receiving a draft key and adapted for connection to an associated center sill, said cheek plate also being formed with a portion adapted to extend beyond the end of said sill, said cheek plate being formed with an outwardly extending substantially horizontal flange and an outwardly extending substantially vertical flange adapted to receive an associated striking casting in the angle formed therebetween for connection therewith.

9. A combined cheek plate and coupler carrier support adapted for connection on the outside of an associated center sill and provided with slots registering with corresponding slots in said sill and flanges bordering said slots for engaging the center sill slots, a portion of said cheek plate being adapted to extend beyond the end of the associated sill and formed with angularly disposed walls providing a pocket for the reception and connection of the adjacent end of an associated striking casting.

In testimony whereof I affix my signature.
DONALD S. BARROWS.
